By his Attorneys,

Inventor

Robert D. Shafer.

C. Snowdon.

UNITED STATES PATENT OFFICE.

ROBERT D. SHAFFER, OF FAYETTE, OHIO.

DESIGN FOR A WRENCH.

SPECIFICATION forming part of Design No. 26,766, dated March 16, 1897.

Application filed January 18, 1897. Serial No. 619,684. Term of patent 7 years.

To all whom it may concern:

Be it known that I, ROBERT D. SHAFFER, a citizen of the United States, residing at Fayette, in the county of Fulton and State of Ohio, have invented a new and original Design for Wrenches, of which the following is a specification.

This invention relates to a new and original design for a wrench; and it has for its object to provide a design of this character that shall be both useful and ornamental.

The leading feature of the design resides in a straight shank provided at one end with a widened head having formed in its outer side a reentrant angular socket whose inner wall presents a straight flat face disposed obliquely to the shank at an obtuse angle thereto, said angular socket having opposite side walls disposed in planes perpendicular to the plane of said inner wall and of different lengths, the shorter side wall having a serrated face and the opposite longer side wall having a concaved face whose concavity is formed on the arc of a circle concentric with the outer extremity of the shorter side wall.

In the drawings, Figure 1 is a perspective view of a wrench embodying the herein-described design. Fig. 2 is a side or plan view thereof.

Referring to the accompanying drawings,

the numeral 1 designates a straight shank having flat sides and substantially rectangular in cross-section. The shank 1 is thickened and widened at one end to form a head 2, somewhat elliptical in form and provided with 35 convexed rounded edges 3. The head 2 has formed in its outer side a reentrant angular socket 4, whose inner wall 5 presents a straight flat face disposed obliquely to the shank 1 at an obtuse angle thereto. The opposite side 40 walls 6 and 7 of the socket 4 are respectively of different lengths and are disposed in planes perpendicular to the plane of the inner wall 5, and the shorter of said walls 6 is formed with a roughened or serrated face. The longer of 45 the two side walls 7 is provided with a concaved face whose concavity is formed on the arc of a circle concentric with the outer extremity of the wall 6.

What I claim is—

The design for a wrench herein shown and described.

In testimony that I claim the foregoing as my own I have hereto affixed my signature in the presence of two witnesses.

ROBERT D. SHAFFER.
